(57) **CLAIM**

The ornamental design for a water play structure, as shown and described.

DESCRIPTION

FIG. 1 is a perspective view of a water play structure, showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

In the drawings, the broken lines represent environment only and form no part of the claimed design.

1 Claim, 6 Drawing Sheets
